UNITED STATES PATENT OFFICE

WILLIAM EMMETT SHACKLETT, OF NEW ALBANY, INDIANA, ASSIGNOR TO SHACKLETT AUTOMATIC CARD FEEDER COMPANY, OF LOUISVILLE, KENTUCKY, A CORPORATION OF KENTUCKY

PRINTING PRESS ATTACHMENT

Application filed May 9, 1924. Serial No. 712,020.

My invention relates to new and useful improvements in an attachment for presses and more particularly to an attachment for feeding cards, such as visiting cards, in proper position relative to the printing, stamping or embossing mechanism to receive the impression.

Another object of the invention resides in the provision of a rotatable table which successively positions the cards to the impressing mechanism the table being rotated intermittently through certain mechanism which is operated from the power mechanism of the press.

15. A further object consists in providing the table with stationary gauge members which properly position the card with its edge overlapping the table to a predetermined distance and adjustable gauge members which 20 are adapted to be moved in unison to adjust the cards transversely of the table, said adjustable gauge members engaging one end of the card adjacent the edge of the table.

Still another object consists in providing, 25 on the table, clamping members to hold the cards, said clamping members being preferably in the form of spring arms or fingers, the cards being received between said spring arms or fingers and the upper surface of the 30 table.

As a still further object I provide a novel 35 form of plate holder, and means for securing the same in the ordinary reciprocating die carriage of the press the plate holder being provided with novel form of clamping mechanism adapted to engage the edges of the plate, said clamping mechanism being adjustable to adapt the plate holder to plates of varying widths and to adjust the angle of 40 the plate relative to the holder.

As a still further object I provide novel 45 means for supporting the attachment relative to the press so that when the press is to be used for purposes other than that of printing or engraving cards the rotatable table may be removed.

With the above and other objects in view, 50 which will appear as the description proceeds, my invention consists in the novel details of construction, and arrangement of

parts, described in the following specification and illustrated in the accompanying drawings, and while I have illustrated and described the preferred embodiments of the invention, as they now appear to me, it will 55 be understood that such changes may be made as will fall within the scope of the appended claims.

In the drawings:

Fig. 1 is a front elevation showing my attachment in position relative to the press. 60

Fig. 2 is a top plan showing my attachment in position relative to the press.

Fig. 3 is a front elevation of the supporting and rotating mechanism for the card supporting table. 65

Fig. 3a is a section on the line 3a, 3a of Fig. 3.

Fig. 4 is a bottom plan of the device shown in Fig. 3. 70

Fig. 5 is a top plan of the card supporting rotatable table.

Fig. 6 is a side elevation, parts broken away, showing the manner of operating the rotatable card supporting table and the reciprocating plate carrier. 75

Fig. 7 is a top plan of the plate supporting carriage.

Fig. 8 is a section on the line 8—8 of Fig. 7. 80

Fig. 9 is a section on the line 9—9 of Fig. 7.

Fig. 10 is a section on the line 10—10 of Fig. 7.

Fig. 11 is a top plan of the removable bearing for the plate carriage shaft. 85

Fig. 12 is a section on the line 12—12 of Fig. 11.

Fig. 13 is a side elevation of a slightly modified arrangement of levers or rods for operating the rotatable card supporting table, and. 90

Fig. 14 is a perspective showing a slightly modified form of plate carrier.

In the drawings 1 and 2 indicate sections of the press frame which are adapted to support the table sections 3, 4, and 5, the section 5, which is shown in dotted lines in Fig. 1 being removable when my attachment is to be used. The inner faces of the frame sec- 100

tions 1 and 2 are spaced apart as more clearly illustrated in Figs. 1 and 2 of the drawings and each section has a depending flange 6 to the inner face of which is secured a supporting bracket 7 by means of screws 8 or other suitable fastenings. These brackets are secured in such a position that their upper surfaces will be below the upper surfaces of the frame sections 1 and 2 for a purpose to be 5 later described. Supported by the brackets 7 is an elongated frame *a* this frame comprising an upper plate 9, a lower plate 10, and end plates 11, the frame being supported horizontally between the depending flanges 6 of 10 the frame sections as is more clearly illustrated in Figs. 1 and 2 of the drawings. The frame *a* is secured in the brackets 7 by means of the set screws 12 or other suitable fastenings, the brackets having a recess in their 15 upper faces for receiving the ends of the frame as quite clearly shown in the drawings.

Rotatably supported in the frame *a*, and extending through the top and bottom plates thereof, is a sleeve 13 which has a vertically 20 extending key 14 formed on the interior thereof. Formed on or secured to the lower end of the sleeve is a ratchet wheel 15 which extends beneath the bottom plate 10 and secured to the sleeve and extending above the 25 upper surface of the plate 10 is a ratchet wheel 16 which, as shown, is of slightly less diameter than the wheel 15. Pivotaly connected to the bottom of the frame *a* is a lever 17 having an L-shaped extension 18 formed 30 on its inner end as more clearly illustrated in Fig. 4 of the drawings. Pivotaly connected at 19 to the L-shaped extension 18 is a pawl 20 which is adapted to engage the ratchet wheel 15 for rotating the sleeve 13 when the 35 lever 17 is operated in a manner to be later described. The outer end of the pawl 20 is held in engagement with the ratchet wheel 15 by means of the coiled spring 21, one end of the coiled spring being connected to the 40 lug 22 formed on the pawl 20 and the opposite end being connected to the lug 23 formed on the plate 24 which is secured to the bottom plate 10 of the frame *a* and forms a bearing for the lever 17, the lever operating between 45 said plate 24 and the bottom plate of the frame. Pivotaly connected at 25 to the upper surface of the plate 10 of the frame is a pawl 26, the inner end of which is adapted to engage the ratchet wheel 16 and prevent 50 rotation of the sleeve in a reversed direction. The pawl is held in engagement with the ratchet wheel by means of the coiled spring 27, one end of the spring being connected to the lug 27 formed on the upper surface of the 55 pawl and the opposite end being connected to a pin 28 extending from the top of the plate 10. Surrounding the sleeve 13 between the ratchet wheel 16 and the top plate 9 of the frame is a coiled spring 29 which is of sufficient strength to provide friction to prevent

free or accidental rotation of the sleeve except when operated through the lever 17 and its associated mechanism.

The mechanism which has so far been described is so positioned relative to the press that the removable section 5 of the table may be placed in position, or removed at will, thereby allowing the press to be used in the ordinary or well known manner. When it is desired to feed cards or similar articles to the press I connect my improved form of rotatable table to the sleeve 13, it being understood that when the rotatable table is used that the section 5 of the press table will be removed. The rotatable table comprises the vertically extending shaft 30 which is of such a diameter as to be received in the sleeve 13 and is provided with the vertically extending keyway 31 to receive the key 14 formed on the interior of the sleeve, and a plate 32 which is formed with the arms 33, 34 and 35. While I have illustrated only three arms it will be understood that any number of arms might equally as well be used. Secured to each of the arms 33, 34 and 35 by means of a screw 36 or other suitable fastening is a spring finger or clamp 37, the outer end of said fingers being positioned adjacent the outer ends of the arms to engage a card 38 which is shown in dotted lines in Fig. 5 of the drawings. In order to properly position the card relative to the arms I provide the gauge blocks 39 which are secured to the upper surfaces of the arms and are adapted to engage the inner longitudinal edge of the 95 cards as shown. In order to adjust the cards transversely of the arms I provide the pivoted levers 40 which are connected to the plate 32 at 41. The outer ends of these levers 40 are bent downwardly around the outer end 100 of the arms 33, 34 and 35 as shown at 42 and this down turned portion of the arms will engage one end of the card as shown. Rotatably connected to the plate 32 is a plate or disc 43 which has an outwardly extending arm 44 formed on its edge. A screw rod 45 is rotatably mounted in the bearing 46 and has its inner end rotatably connected at 47 to the arm 44, a finger hold or knurl 48 being formed on the outer end of the rod so that it may 105 be easily rotated. Each of the levers 40 is connected to the plate or disc 43 by a link 49. When the screw rod 45 is rotated it will rotate the plate or disc 43 and through means of the links 49 swing the levers 40 on their pivots 41, the down turned ends 42 engaging the ends of the cards and adjusting them transversely of the arms. It will thus be seen that the gauge blocks 39 and levers 40 form 110 means to properly position the cards and when the levers are adjusted for the particular size card being used it is only necessary when positioning new cards of the same size, to engage them beneath the ends of the spring fingers or clamps 37.

The lever 17 is operated from the drive shaft 50 of the press which has an eccentrically positioned pin 51 on each end, only one of said pins being shown in the drawings. Pivotal connected at 52 to a reduced extension on the eccentrically positioned pin on one end of the shaft is a bar 53 which has its opposite end pivotally connected at 54 to a substantially vertically extending lever 55 which is swiveled to the base of the press. Pivotal connected at 56 to the upper end of the lever 55 is a bar or link 57 the opposite end of which is connected at 58 to the lever 17. It will thus be seen that as the drive shaft 50 rotates it through means of the bar 53 swings the lever 55 which through means of the link or bar 57 swings the lever 17 and through means of the pawl 20 rotates the sleeve 13 in a step by step movement. The sleeve will be rotated in one direction at all times and is held in position against reverse movement by means of the pawl 26, the coiled spring 29 preventing rotation of the sleeve without movement of the lever 17.

At 59 I have indicated generally a reciprocating plunger which is of the form now commonly used upon presses for making an impression and as this plunger forms no part of my present invention a detailed description thereof is not necessary. The plunger is operated through means of the frame 60 which has the depending arms 61 each having an opening adjacent its lower end through which the eccentrically positioned pins 51 will extend, the plunger being lowered for making an impression upon the lowering of the frame 60 and returning to its raised or normal position when the frame is raised.

The impression for printing or engraving the card is taken from a plate 62 which is carried by a plate holder 63 which is supported in a sliding table or frame indicated generally at 64. The frame 64 is of the construction now commonly used in presses with the exception that for properly connecting or positioning the plate holder I form the front of the table or frame as a detachable element which comprises the bar 65 which will be secured to the frame or table by means of screws or other suitable fastenings. The bar 65 is formed on its upper surface, intermediate its ends, with the recessed bearing 66 and a removable bearing plate 67, the bearing plate 67 being held in position in the recess 66 by means of the screws 68 which have the flattened or straight portion 69. The bearing plate 67 has a notch or recess 70 formed in the upper surface at each end the head of the screw 68 being received in the recess 70 when the screw is rotated to bring the flattened or straight portion 69 out of alignment with the ends of the recess. When the flattened or straight portion 69 extends parallel or in alignment with the end of the recess the bearing plate may be easily removed. The plate

holder 63 is in the form of a block or casting which has a transversely extending screw threaded opening to receive the threaded shaft 71 whereby it may be adjusted with respect to the table or frame 64. One end of the shaft 71 is reduced as shown at 72 and received in a recess formed in the back bar of the table or frame and the opposite end is formed with the collar 72^a and flange 73, the collar 72^a being received in a cut-out portion of the recess 66 and the flange 73 engaging the outer face of the bar 65. The end of the shaft projecting beyond the flange 73 is of irregular shape as shown at 74 so that the shaft may be rotated by a wrench or other suitable instrument. The bearing plate 67 has a cut-out portion 75 to receive the collar 72^a and a groove 76 to receive the shaft. When the screw shaft 71 is rotated it will adjust the plate holder 63 relative to the table or frame 64. The plate holder is provided in its upper face with a transversely extending groove or recess 77 which is preferably of dove-tail formation to receive the dove-tail slide 78 which is adapted to be operated by means of the screw 79. The slide is provided with the projection 80 which is adapted to engage one longitudinal edge of the plate 62 as more particularly illustrated in Fig. 7 of the drawings. Extending through the plate holder 63 on opposite sides of the threaded opening through which the shaft 71 passes is an opening 81 which terminates in an enlarged recess 82 as more clearly illustrated in Fig. 10 of the drawings. Extending through each of the openings 81 is a threaded rod 83 which is provided on one end with the head 84. Slidably mounted in each of the enlarged recesses 82 is an interiorly threaded sleeve 85, the threaded rod 83 passing through the threaded opening of the sleeve whereby the sleeve may be adjusted relative to the plate holder. The sleeves are provided with the projections 86 which extend above the upper surface of the plate holder and form abutments for the longitudinal edge of the plate 62 opposite to that edge engaged by the projection 80. A coiled spring 87 is received in each of the enlarged recesses 82, one end of the said coiled spring engaging the inner wall of the recess and the opposite end engaging the inner end of the sleeve 85, the spring surrounding the threaded rod 83 as more particularly illustrated in Fig. 10 of the drawings. When the rod 83 is rotated it will adjust the sleeve 85 and the coiled spring 87 will force the same outwardly so as to hold the head 84 of the rod 83 tightly against the face of the holder. The projections 86 on the sleeves 85 extend into notches 88 formed in the face of the holder and the projections being received in these notches prevent rotation of the sleeves 85 when the threaded rods 83 are operated. The plate 62 is placed on top of the plate holder 63 as more particularly

illustrated in Fig. 7 of the drawings and is clamped between the projections 80 and 86. By adjusting the screw 79 the slide 78 is moved and may be adjusted to accommodate plates of various widths. Very often in cutting the name to be printed or engraved in the plate 62 the line will not be exactly straight and it is necessary to swing the plate so that the name will be in a straight line. This adjustment may be accomplished by the threaded rods 83 which move the sleeves 85. The projections 86 on the sleeves engaging the edge of the plate will swing the same to the angle desired. In order that the name will be properly positioned on the card the plate holder is adjustable through means of the threaded rod 71 which moves the plate holder relative to the table or frame 64.

The table or frame 64 is adapted to be reciprocated so as to draw the plate beneath the inking mechanism, not shown, and to then position the same beneath the card. A rod 89 is secured to the frame or table 64 and will be operated through means of suitable mechanism connected to the driving shaft of the press, such as by a link or rod 90.

In Fig. 13 of the drawings I have shown a slightly modified form of means for rotating my card carrying table. In this form of the invention a rod 91 is connected at one end to the eccentric and at the opposite end is connected to the arm 92 of a bell crank lever which is pivotally mounted upon a rod 93 which may be supported with the press in any suitable manner. To the other arm 94 of the bell crank lever is connected, for swinging movement, a rod or bar 95 which has connected thereto a bifurcated member 96 which is adjustable by means of the turn screw 97. The bifurcated member 96 will be connected to the arm 17 for rotating the sleeve 13.

In Fig. 14 of the drawings I have shown a slightly modified form of the plate holder 63. In this form of the invention a rib 98 is formed on or secured to the undersurface of the holder and will operate in a guide-way formed in the press. In all other respects this form of plate holder is of the same construction as described for the preferred form.

From the above detail description it will be noted that I have provided novel mechanism for using well known forms of printing presses for printing visiting cards or the like the cards being fed by a step by step movement into position to receive the impression from the printing mechanism. There being three arms to the rotatable table as one card is receiving the impression, that card which has previously received the impression is being removed by the operator and another card is being placed in position. The table is intermittently rotated by the pawl and ratchet mechanism and the rotation will be so timed as to have the cards fed into position to receive the impression at the time that the plunger is

in raised position and the plate holder or carriage is in its rearwardmost position being inked. After the card has been properly positioned the plate holder or carriage is fed to a position beneath the card and then the plunger is lowered and the impression made. I have also provided novel means for holding and adjusting the plate.

Having fully described my invention what I claim as new and desire to secure by Letters Patent is:

1. A rotatable carrier for feeding cards or the like to a printing press comprising a supporting plate for the cards, a pivoted lever carried by the plate and engageable with the cards, and means for adjusting the lever for positioning the cards relative to the plate.

2. A rotatable carrier for feeding cards or the like to a printing press comprising a plate for supporting the cards, a plurality of levers pivotally connected to the plate and engageable with the cards for positioning the same relative to the plate, and means for operating the levers in unison.

3. A carrier for feeding cards or the like to a printing press comprising a supporting frame, a sleeve rotatably carried by the frame, a card supporting plate having a shank adapted to be received in the sleeve, and means for rotating the sleeve.

4. A carrier for feeding cards or the like to a printing press comprising a supporting frame, a sleeve rotatably mounted in the frame, a card supporting table having a depending portion received in the sleeve, and means for rotating the sleeve.

5. In combination with a printing press, a frame carried by the press, a sleeve rotatably mounted in the frame, a card supporting plate removably carried by the sleeve, an arm pivotally connected to the frame and adapted to rotate the sleeve for feeding the cards to the press, and means connected to the arm and operable by the power driving mechanism of the press for operating the arm.

6. In combination with a printing press, a frame carried by the press, a sleeve rotatably mounted in the frame, a carrier connected to the sleeve for feeding cards or the like to the press, a ratchet carried by the sleeve, a lever pivotally connected to the frame, a pawl carried by the lever and engageable with the ratchet for rotating the sleeve, and means for operating the lever from the press operating mechanism.

7. In combination with a printing press, a frame, a sleeve rotatably mounted in the frame, a card carrier removably carried by the sleeve, means for rotating the sleeve in one direction to feed the cards to the press, and means for holding the sleeve against rotation in the opposite direction.

8. In combination with a printing press, a frame, a sleeve rotatably mounted in the frame, a card carrier connected to the sleeve,

yieldable means for holding the sleeve against accidental rotation, means for positively rotating the sleeve in one direction to feed the cards to the press, and means for preventing rotation of the sleeve in the opposite direction.

9. A press, a turn-table for feeding stock thereto, supporting structure therefor fastened to the press, and an adjustment for simultaneously adjusting stock engaging portions of the turn-table to adapt the turn-table to use with varying sizes of stock.

10. A device for feeding cards or the like to a printing press including brackets secured to the press, a frame mounted in the brackets, a sleeve rotatably carried by the frame, a carrier supported by the sleeve and removable therefrom, and means for rotating the sleeve.

20. 11. A device for feeding cards or the like to a printing press including brackets secured to the press, a frame detachably mounted in the brackets, a rotatable sleeve carried by the frame, a carrier supported by the sleeve and removable therefrom, and means for rotating the sleeve.

12. Feeding mechanism for printing presses comprising a plurality of article carriers adapted to be moved into feeding relation to a printing mechanism, an adjustable article stop on each carrier, and means connecting a plurality of said article stops effective to adjust them simultaneously with respect to said carriers.

30. 13. Feeding mechanism for printing presses comprising a plurality of article carriers adapted to be moved into feeding relation to a printing mechanism, an article stop pivoted to each carrier, and connecting means between a plurality of said pivoted article stops effective to pivotally adjust them simultaneously.

45. 14. Feeding mechanism for printing presses comprising a plurality of article carriers adapted to be moved into feeding relation to a printing mechanism, an adjustable article stop on each carrier, and a single member common to a stop of each of said carriers effective to adjust them simultaneously with respect to said carriers.

50. 15. Feeding mechanism for printing presses comprising a plurality of article carriers adapted to be moved into feeding relation to a printing mechanism, an adjustable article stop on each carrier, a member on each carrier having adjustable connection with the article stop thereon, a single operator common to the members of all carriers effective to move them simultaneously, thereby to effect adjustments of a stop of each carrier simultaneously, and means for moving said operator.

60. 16. Feeding mechanism for printing presses comprising a plurality of adjustable article carriers adapted to be moved into feed-

70. ing relation to a printing mechanism, means for simultaneously adjusting said carriers, and adjustable article stop on each carrier, and means for simultaneously adjusting a plurality of said article stops when the carriers are at rest.

75. 17. Feeding mechanism for printing presses comprising a plurality of adjustable article carriers adapted to be moved into feeding relation to a printing mechanism, means for simultaneously adjusting said carriers, an article stop on said carrier adjustable with respect thereto, and means for so adjusting said article stops in any adjusted position of said carriers.

80. 18. The combination with a press having a removable table portion, of means for feeding cards or the like to the press, said means including a support normally positioned beneath the removable portion of the table, and a rotatable carrier adapted to be carried by the support when the removable portion of the table is removed.

85. 19. The combination with a press having a removable table portion, of means for feeding cards or the like to the press, said means including a removable support adapted to be normally positioned beneath the removable portion of the table, and a rotatable carrier adapted to be carried by the support when the removable portion of the table is removed.

90. 20. The combination with a press having a removable table portion, of means for feeding cards or the like to the press, said means including brackets positioned beneath the removable portion of the table, a frame carried by the brackets and normally positioned beneath the removable portion of the table, and a rotatable carrier carried by the frame when the removable portion of the table is removed.

100. 110. 21. The combination with a press having a removable table portion, of means for feeding cards or the like to the press, said means including brackets positioned beneath the removable portion of the table, a frame carried by the brackets and positioned beneath the removable portion of the table, a rotatable carrier adapted to be carried by the frame when the removable portion of the table is removed, and means carried by the frame for rotating the carrier.

115. 120. 22. The combination with a press having a removable table portion, of means for feeding cards or the like to the press, said means including brackets positioned beneath the removable portion of the table, a frame carried by the brackets and positioned beneath the removable portion of the table, a rotatable carrier adapted to be carried by the frame when the removable portion of the table is removed, and means carried by the frame and operable by the press operating means for rotating the carrier.

23. The combination with a press having the usual impression members and a removable table portion, of means for feeding cards or the like to said impression members of the press, said means including a frame positioned beneath the removable portion of the table, and a rotatable carrier adapted to be supported by the frame when the removable portion of the table is removed, said carrier including card or the like supporting surfaces adapted to position the cards beneath the impression members.

24. Feeding mechanism for printing presses comprising a plurality of article carriers adapted to be moved successively into feeding relation to a printing mechanism, an adjustable article stop on each carrier, and means connecting a plurality of said article stops effective to adjust them simultaneously with respect to said carriers.

25. Feeding mechanism for printing presses comprising a plurality of article carriers adapted to be moved successively into feeding relation to a printing mechanism, an article stop pivoted to each carrier, and connecting means between a plurality of said pivoted article stops effective to pivotally adjust them simultaneously.

26. Feeding mechanism for printing presses comprising, in combination with a plurality of adjustable article carriers adapted to be moved successively into feeding relation to a printing mechanism, and means for adjusting them equal amounts simultaneously to vary their relation to the printing mechanism; an adjustable article stop on each carrier, and connecting means between the article stops of a plurality of said carriers effective to adjust them simultaneously.

27. Feeding mechanism for printing presses comprising a plurality of article carriers adapted to be moved successively into feeding relation to a printing mechanism, an adjustable article stop on each carrier, and a single member common to a stop of each of said carriers effective to adjust them simultaneously with respect to said carriers.

28. Feeding mechanism for printing presses comprising a plurality of article carriers adapted to be moved successively into feeding relation to a printing mechanism, an adjustable article stop on each carrier, a member on each carrier having adjustable connection with the article stop thereon, a single operator common to the members of all carriers effective to move them simultaneously, thereby to effect adjustments of a stop of each carrier simultaneously, and means for moving said operator.

29. Feeding mechanism for printing presses comprising a plurality of adjustable article carriers adapted to be moved successively into feeding relation to a printing mechanism, means for simultaneously adjusting said carriers, an adjustable article stop on each car-

rier, and means for simultaneously adjusting a plurality of said article stops when the carriers are at rest.

30. Feeding mechanism for printing presses comprising a plurality of adjustable article carriers adapted to be moved successively into feeding relation to a printing mechanism, means for simultaneously adjusting said carriers, an adjustable article stop on each carrier, and means independent of said first mentioned means for adjusting a plurality of said article stops simultaneously.

31. Feeding mechanism for printing presses comprising a plurality of adjustable article carriers adapted to be moved successively into feeding relation to a printing mechanism, means for simultaneously adjusting said carriers, an article stop on said carrier adjustable with respect thereto, and means for so adjusting said article stops in any adjusted position of said carriers.

32. In combination with a printing press, a support, a rotatable table carried by the support, for feeding stock to the press, a notched disc carried by the rotatable table, means for intermittently rotating the table, and means engageable with the notched disc for positively positioning the table relative to the press after each rotation thereof.

33. In combination with a printing press, a support, a rotatable table carried by the support, for feeding stock to the press, a notched disc carried by the rotatable table, means for intermittently rotating the table, and a pawl engageable with the notched disc for positively positioning the table relative to the press after each rotation thereof.

In testimony whereof I hereunto affix my signature.
